UNITED STATES PATENT OFFICE.

GEORGE S. MERRILL, OF CLEVELAND, OHIO, ASSIGNOR TO J. M. WOODWARD, OF CLEVELAND, OHIO.

DESIGN FOR AN EMBLEM.

No. 39,798.

Specification for Design.

Patented Feb. 2, 1909.

Application filed November 13, 1908. Serial No. 462,532. Term of patent 7 years.

To all whom it may concern:

Be it known that I, GEORGE S. MERRILL, a citizen of the United States, residing at Cleveland, in the county of Cuyahoga and State of Ohio, have invented a new, original, and ornamental Design for an Emblem, of which the following is a specification, reference being had to the accompanying drawing, forming a part thereof.

The figure is an elevation of said emblem.

I claim:

The ornamental design for an emblem, substantially as shown.

GEORGE S. MERRILL.

Witnesses:

J. W. WOODWARD,
H. R. SULLIVAN.
